UNITED STATES PATENT OFFICE

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS

PUMP WORKING HEAD

Application filed June 29, 1931. Serial No. 547,687.

This invention relates to a working head for deep well pumps.

Geared working heads have been objectionable because of the multiplicity of moving parts required and the uncertainty of lubrication especially under adverse operating conditions, as, for example, in farm installations where the outfit is called upon to take care of the entire farm pumping service and is seldom, if ever, inspected to see if it is getting proper lubrication. It is, therefore, the principal object of my invention to provide a hydraulically operated working head utilizing oil as the working fluid and designed so that all of the moving parts, the number of which is reduced to a minimum, far below what is required in a geared working head, operate continuously immersed in oil. This makes for a very substantial outfit and one which will last practically indefinitely. As will soon appear, the head is designed to operate efficiently even when the oil level in the tank has dropped down to a very small fraction of the original supply. In other words, where a geared working head, to operate quietly and with proper lubrication, relied upon the presence of a definite amount of oil in the reservoir, this head is unaffected by a considerable drop in the oil level.

Other objects of my invention, more specifically stated, consist in:

1. The mounting of the hydraulic motor rigidly on the base, and the fastening of the oil tank onto the side of the motor, thereby utilizing the motor itself as one side of the tank, and locating the joint so that, if any leakage develops, it can be easily taken care of;

2. Mounting the valve chest directly on the side of the hydraulic motor inside the tank, and providing a face plate for the oil pump directly on the valve chest, for support of the pump with the valve chest on the motor, immersed in the oil in the tank;

3. Providing a hole in the outer end wall of the tank for extension therethrough of the oil pump shaft, and an adjustable prop for the outer end of the tank on the base, permitting adjustment in the elevation of the

tank to bring the hole in accurate alignment with the shaft, and

4. Providing covers cooperating with the oil tank and the hydraulic motor to completely enclose all of the moving parts for protection thereof, and prevent dirt or water from getting into the oil.

The invention is described hereinafter by reference to the accompanying drawings in which—

Figs. 1 and 2 are, respectively, a side and plan view of the working head of my invention;

Fig. 3 is a longitudinal vertical section through the head on a larger scale;

Fig. 4 is a sectional detail corresponding to a portion of Fig. 3 with parts shown in a different position;

Fig. 5 is a cross-section on the line 5—5 of Fig. 3;

Fig. 6 is a longitudinal horizontal section on the line 6—6 of Fig. 3;

Fig. 7 is a horizontal section on the line 7—7 of Fig. 3; and

Fig. 8 is a vertical sectional detail in the plane of the line 8—8 of Fig. 7.

The same reference numerals are applied to corresponding parts throughout the views.

The working head has a base 10 arranged to be set on a suitable foundation over the well casing alongside the usual drop pipe which, as is well known, is disposed substantially centrally in the well casing and has the pump rod 11 extending downwardly therein. The drop pipe is arranged to thread at 12 into the head 13, from which the discharge pipe 14 extends as shown, the same being extended to the usual storage tank forming a part of the water supply system. An electric motor 15 is mounted on one end of the base, and a hydraulic motor 16 together with its oil tank 17 on the other end. The oil in the tank, as will soon appear, constitutes the working fluid and, at the same time, the lubricant for such of the parts of the working head as require lubrication. A light oil is suitable for the purpose but in extremely cold weather it is a good practice to pour in kerosene to keep the fluid from becoming too heavy. The hydraulic motor 100

16 has a valve chest 18 and oil pump 19 provided in connection therewith in the tank 17. The pump 19 is driven through a suitable coupling connection 20 with the armature 5 shaft 21 of the electric motor 15 and pumps oil directly from the inside of the tank 17 and delivers it through the valve chest 18 to the hydraulic motor 16 for reciprocation of the plunger rod 22, which is coupled as indicated at 23 with the pump rod 11. So much for a general understanding of the working head of this invention. This working head is similar to that disclosed in my copending application, Serial No. 372,632, filed June 21, 15 1929, now Patent Number 1,906,965, and embodies the various improvements in construction and arrangement indicated above and described in detail hereinafter.

The hydraulic motor 16, in accordance 20 with the present invention, comprises a cylinder block 24 providing a cylinder 25 between opposite side walls 26 to which the cylinder is joined by a front wall 27 and top and bottom walls 28 and 29. The cylinder block 24 is fastened to the base 10 by studs 30 extending from the bottom wall 29 through holes in the base and having nuts 31 threaded thereon under the base. This obviously provides good rigid support for the hydraulic 30 motor such that there is very little danger of the same working loose. A plate 32 is bolted to the bottom wall 29 to close the lower end of the cylinder 25. A one-piece cast yoke member 33 is mounted on top of the cylinder block 24 and fastened thereto as by bolts 34. A guide post 35 extends downwardly from the upper end of the yoke and has the hollow rod 36 of a piston 37 slidably thereon. The piston 37 is reciprocable in the cylinder 25 by means of the oil delivered first to one end of the cylinder and then the other. A ring 38 in which the piston rod 36 has a close working fit, is clamped in place in the upper end of the cylinder 25 in the bolting of 40 the yoke 33 on the cylinder block. The ports for the opposite ends of the cylinder appear at 39 and 40 of Figs. 3 and 4. A two-piece crosshead 41 is arranged to be secured to the upper end of the piston rod 36 by means 50 of bolts 42 and at one end has connection with the plunger rod 22 by means of the nuts 43 threaded on the rod, and at the other end has connection with the stem 44 of a pilot valve 45, whereby to reciprocate the pump 55 rod 11 in the reciprocation of the piston, and operate the pilot valve 45 in timed relation therewith.

The oil tank 17, according to the present 60 invention, is arranged to be bolted onto the hydraulic motor for support and so as to utilize the motor as one side of the tank. A flat face 46 is provided on the bottom wall 29 in the same plane with a flat face 47 on the side walls 26, and the tank 17 is provided 65 with complementary flat faces 46' and 47' on in accordance with my other copending ap-

the bottom and side walls as best appears in Fig. 6, whereby to permit the fastening of the tank to the cylinder block 24 of the motor with an oil-tight joint, as by means of bolts 48 passed freely through holes in bosses 70 formed in the block 24 and threaded in bosses 49 provided on the inside of the tank 17. In addition, a pair of bolts 50 are suitably extended from the bottom of the tank 17 and threaded into the cylinder block 24 to make 75 for a better joint. A gasket is suitably interposed between the meeting faces 46—46' and 47—47' as indicated in Fig. 6 to insure an oil-tight joint. In this way, a reservoir 51 for oil is provided jointly by the cylinder block 24 and tank 17, the block forming one side of the tank, and the joint between these parts is in full view so that, if any leak develops, it will be noticed immediately and can be attended to easily. The top of the tank 17 is closed except for a small filler opening 52 in the neck 53 provided preferably immediately alongside of the cylinder block 24, whereby to permit extension of the pilot valve stem 44 through this opening and also permit closing of the opening by a cover 54 fastened directly to the side of the hydraulic motor as by means of screws 55 threaded into the yoke 33. Another cover 56 for the lower front portion of the motor is fastened as by means of screws 57 to the cylinder block 24, and still another cover 58 similar to the cover 54 is fastened to the opposite side of the yoke 33 as by means of screws 59. The discharge pipe 14 extends through a 80 hole 60 in the lower front cover 56 as indicated in Fig. 3. This construction provides complete enclosure of all of the working parts for protection thereof and neater external appearance of the working head, as will be apparent upon inspection of Fig. 1, and moreover seals the unit against any dirt and water, so that the working parts remain clean and the oil uncontaminated.

The valve chest 18 is in the form of a 85 casting 61 arranged to be bolted as at 62 to the cylinder block 24 with its ports 63 and 64 in direct communication with the ports 39 and 40 of the cylinder 25 as best appears in Figs. 3 and 6. The outer end of the casting is made in the form of a face plate for the pump 19 as appears at 65 whereby to support the pump along with the valve chest on the hydraulic motor 16, immersed in the oil in the tank 17. The housing 66 of the pump 19 and its other face plate 67 are bolted as at 68 to the face plate 65 to complete the assembly of the pump. The pump is made generally along the lines of that disclosed in my copending application, Serial No. 300,666, filed August 20, 1928, and has a suction chamber 69 on one side of the pumping gears and a discharge chamber 70 on the other side. The suction chamber 69, 120 with complementary flat faces 69' and 70' on in accordance with my other copending ap-

lication, communicates directly with the reservoir 51 in the tank 17 through an inlet port 71. The discharge chamber 70 communicates with the valve chest 18 through a discharge port 72. Thus, the oil in the continuous operation of the pump is pumped from the reservoir 51 in the tank and discharged under pressure into the valve chest at 72. Now, the valve chest has, in addition to the pilot valve 45, a main valve 45' mounted for reciprocation therein. As described in my first mentioned copending application, the pilot valve is shifted by engagement of the crosshead 41 with stops 73 and 74 provided on the stem 44 and, when shifted to one-limit position, it causes the main valve to be shifted under hydraulic pressure to an opposite limit position, whereby alternately to establish communication between the port 39 and port 72 and then between port 40 and port 72, and so on, to reciprocate the piston 37 in the cylinder 25. The main valve, when in a position establishing communication between the port 72 and one of the two ports 39 and 40, establishes communication between the exhaust port 75 and the other port of the cylinder, so that, as oil is admitted under pressure to one end of the cylinder, the oil in front of the piston is allowed to escape and be discharged back into the reservoir 51. Hoods 76 are provided on opposite sides of the valve chest to deflect the oil downwardly from the exhaust port 75 toward the bottom of the reservoir, similarly as described in my first mentioned copending application. This prevents excessive splashing of oil so that there is no danger of oil being lost through the filler opening 52. The driven shaft 77 of the pump 19 projects through a hole 78 in the outer end wall of the tank 17 for coupling connection at 20 with the armature shaft 21 of the electric motor 15. Inasmuch as the hole 78 is so remote with reference to the point of attachment of the tank to the cylinder block 24 of the hydraulic motor, and the shaft 77 is likewise remote with reference to the point of attachment of the pump and valve chest on the cylinder block, it becomes a problem to secure accurate alignment between the shaft 77 and the hole 78. Accurate alignment is, of course, essential because there would otherwise be an unnecessary drag on the motor 15 and premature wear of the shaft 77 and at the hole 78, and the working head would not operate as smoothly and quietly as desired. For this reason, I contemplate providing a jack screw 79 below the outer end of the tank 17 threaded in the base 10 and arranged to be locked by means of a lock nut 80. The screw 79 can be adjusted easily to secure exact alignment between the hole 78 and shaft 77. A pair of sealing rings 81 and 82 are provided on the shaft 77 inside the tank 17 between the pump and the wall of the tank, the rings

being urged apart by means of a coiled compression spring 83 so that the ring 81 seals the pump against leakage along the shaft, and the ring 82 seals the tank against leakage along the shaft.

Referring to Fig. 8 it will be observed that an arm 84 projects laterally from the upper end of the plunger rod 22 whereby to reciprocate another rod 85 affixed to a plunger 86 working in a cylinder 87 mounted on the head 13 in the usual way. It has been common practice in the past to provide a pet-cock normally leaving the lower end of the cylinder 87 open to the atmosphere except when additional air is needed in the storage tank, whereupon, the pet-cock was arranged to be closed to cause air to be forced into the tank upon each down-stroke of the plunger 86. The complete enclosure of the working head, however, makes the use of a pet-cock impractical because it would necessitate the removal of the cover 56 whenever the pet-cock was to be closed. In accordance with my invention, I have therefore, provided a screw plug 88 having a universal joint connection 89 with an extension handle 90 reaching through a hole in the lower front cover 56. The plug 88 is normally kept open and, when additional air is needed in the storage tank, the plug is closed by turning the handle 90. Then, on each upstroke of the plunger 86, air is trapped in the cylinder 87 and is forced into the tank on the down-stroke, in a manner well known in this art.

It is believed the foregoing description conveys a good understanding of all of the objects and advantages of my invention. It is manifest that various changes in design and construction might be made without seriously departing from the spirit and scope of the invention. The appended claims have, therefore, been drawn to cover all legitimate modifications and adaptations.

I claim:

1. A unit of the character described comprising in combination, a base, a hydraulic motor of the reciprocating type mounted with the cylinder block thereof vertically disposed on and secured to the base in upright position and with the piston rod thereof extending upwardly therefrom, a tank for working fluid rigid with the cylinder block on one side thereof for support on the base, said arrangement also permitting of direct discharge of spent working fluid from the motor into the tank, a pump disposed in said tank arranged to pump fluid directly therefrom and deliver the fluid directly to the motor for operation thereof, means for driving the pump having connection therewith through a wall of the tank, said hydraulic motor having a yoke extending upwardly from the cylinder block thereof having a guide thereon for the piston rod, the top of said tank being open for filling and other purposes, and a cover co-

operating with the open top of the tank and the aforesaid yoke to close the tank.

2. A unit of the character described comprising in combination, a base, a hydraulic motor of the reciprocating type mounted with the cylinder block thereof vertically disposed on and secured to the base in upright position and with the piston rod thereof extending upwardly therefrom, a tank for working fluid rigid with the cylinder block on one side thereof for support on the base, said arrangement also permitting of direct discharge of spent working fluid from the motor into the tank, a pump disposed in said tank arranged to pump fluid directly therefrom and deliver the fluid directly to the motor for operation thereof, means for driving the pump having connection therewith through a wall of the tank, said hydraulic motor having a yoke extending upwardly from the cylinder block thereof having a guide thereon for the piston rod, the top of said tank being open for filling and other purposes, a cover cooperating with the open top of the tank and the aforesaid yoke to close the tank, means on the diametrically opposite side of the cylinder block from the tank providing an operating connection between the piston rod and the device to be operated thereby, and cover means cooperating with the cylinder block and yoke to enclose the last mentioned means.
3. A unit of the character described comprising in combination, a base, a hydraulic motor of the reciprocating type mounted with the cylinder block thereof vertically disposed on and secured to the base in upright position and with the piston rod thereof extending upwardly therefrom, a tank for working fluid rigid with the cylinder block on one side thereof for support on the base, said arrangement also permitting of direct discharge of spent working fluid from the motor into the tank, a pump disposed in said tank arranged to pump fluid directly therefrom and deliver the fluid directly to the motor for operation thereof, means for driving the pump having connection therewith through a wall of the tank, said hydraulic motor having a yoke extending upwardly from the cylinder block thereof having a guide thereon for the piston rod, the top of said tank being open for filling and other purposes, a closure for the tank, means on the diametrically opposite side of the cylinder block from the tank providing an operating connection between the piston rod and the device to be operated thereby, and cover means cooperating with the cylinder block and yoke to enclose the last mentioned means.
4. In an apparatus of the character described, the combination, in a unitary assembly, of a base, a working cylinder supported on said base, a fluid operated piston in said cylinder having the rod thereof extending from the cylinder for convenient connection

with the device to be operated, whereby to reciprocate said device in the reciprocation of the piston, a tank for working fluid rigid with the cylinder on one side thereof, whereby the same is supported on the base by said cylinder and whereby direct discharge of spent working fluid is permitted from the cylinder into the tank, a pump disposed in said tank arranged to pump fluid directly therefrom and deliver the fluid directly to the cylinder for operation of the piston, a drive motor supported on said base having connection with the pump through a wall of the tank, and valve mechanism in said tank communicating with the outlet of the pump and arranged to establish communication for said outlet alternately with the opposite ends of said cylinder to reciprocate the piston, said valve mechanism being arranged to discharge spent fluid from the cylinder directly back into the tank.

5. In an apparatus of the character described, the combination in a unitary assembly, of a base, a working cylinder supported on said base, a fluid operated piston in said cylinder for convenient connection with the device to be operated, whereby to reciprocate said device in the reciprocation of the piston, a tank for working fluid rigid with the cylinder on one side thereof, whereby the same is supported on the base by said cylinder and whereby direct discharge of spent working fluid is permitted from the cylinder into the tank, a pump for supplying working fluid under pressure alternately to opposite ends of said cylinder rigidly supported on said cylinder in said tank, whereby the same is adapted to pump fluid directly from the tank and deliver the fluid directly to said cylinder, a drive motor supported on said base having connection with the pump through a wall of the tank, and valve mechanism in said tank communicating with the outlet of the pump and arranged to establish communication for said outlet alternately with the opposite ends of said cylinder to reciprocate the piston, said valve mechanism being arranged to discharge spent fluid from the cylinder directly back into the tank.

6. An apparatus as set forth in claim 4 including auxiliary supporting means for the tank between the base and the bottom of the tank, said means being disposed adjacent the outer end of the tank spaced from the cylinder and being adjustable relative to the tank and base as desired, whereby to make the tank rigid relative to the base.

7. A unit of the character described comprising in combination, a base, a hydraulic motor of the reciprocating type mounted with the cylinder block thereof vertically disposed on and secured to the base in upright position and with the piston rod thereof extending upwardly therefrom, a tank for working fluid rigid with the cylinder block on one side

thereof for support on the base, said arrangement also permitting of direct discharge of spent working fluid from the motor into the tank, a pump disposed in said tank arranged
5 to pump fluid directly therefrom and deliver the fluid directly to the motor for operation thereof, means for driving the pump, valve mechanism in said tank communicating with the outlet of the pump and arranged to establish communication for said outlet alternately with the opposite ends of said cylinder block to reciprocate the piston, said valve mechanism being arranged to discharge spent fluid from the cylinder directly back into the
10 tank, a yoke for said hydraulic motor extending upwardly from the cylinder block and having a guide thereon for the piston rod, means providing an operating connection between the piston rod and the valve mechanism
15 and cover means cooperating with the cylinder block and yoke to enclose the last mentioned means.
20

8. A unit as set forth in claim 7 wherein the top of said tank is open for filling and
25 other purposes and wherein the cover means set forth in claim 7 is constructed so as to close the open top of said tank.

In witness of the foregoing I affix my signature.
